Specification of Letters Patent. Patented Aug. 19, 1913.

Application filed February 4, 1913. Serial No. 746,234.

To all whom it may concern:

Be it known that I, CLIO B. YAW, citizen of the United States, and resident of Arlington, in the county of Hudson and 5 State of New Jersey, have invented certain new and useful Improvements in Type-Writing Machines, of which the following is a specification.

My invention relates to typewriting machines and is directed more particularly to 10 the paper controlling, guiding or feeding means in such machines.

It has been common heretofore to employ 15 loose-leaf work sheets provided with key-hole slots, such, for example, as those shown in Fig. 5 of the accompanying drawings. These key-hole slots enable the sheets to be bound in a loose-leaf binder after the sheets have been filled in on the machine. Such 20 sheets are employed in condensed record billing and other characters of work, and difficulty has been encountered heretofore in feeding such sheets through the machine, by reason of the liability of the edges of 25 the work sheets, where the key-hole slots are provided, catching against certain of the paper feeding or guiding devices and paper apron, etc. Moreover, difficulty has been found heretofore by reason of the liability 30 of the lower or bottom edge of the work sheet catching on the front edge of the paper apron when the sheet has been fed forwardly a sufficient distance to carry the bottom edge of the work sheet above the 35 front edge of the paper apron, and when an attempt is then made to back up the sheet.

The main object of my present invention is to overcome these and other difficulties, and to provide simple and efficient means 40 for effectively guiding a work sheet as it is being fed either backwardly or forwardly through the machine.

To the above and other ends which will hereinafter appear, my invention consists 45 of the features of construction, arrangements of parts and combinations of devices set forth in the following description and particularly pointed out in the appended claims.

50 In the accompanying drawings wherein like reference characters designate corresponding parts in the different views, Fig.

ure 1 is a transverse sectional view of a portion of a carriage of a typewriting machine embodying my invention. Fig. 2 is a detail rear elevation of one form of paper finger carrying a margin feed roller and constructed in accordance with my present invention. Fig. 3 is a like view of another form of the construction. Fig. 4 is a fragmentary longitudinal sectional view of the device shown in Fig. 3. Fig. 5 is a fragmentary front elevation of a carriage equipped with a paper finger such as is shown in Figs. 1 and 2.

I have shown my invention in the present instance embodied in a front strike machine, the carriage shown being that of a No. 10 or No. 11 Remington machine. It should be understood, however, that the invention 70 may be embodied in various styles of typewriting machines. The carriage comprises end plates 1 united by cross bars 2, 3 and 4. A cylindrical rotative platen 5 is mounted in the carriage on a platen shaft 6 in the usual manner. Front and rear paper feed rollers 7 and 8 respectively coöperate with the platen in the usual manner, such rollers extending through openings in a paper apron 9 which terminates at its forward 80 end at the line indicated by the reference numeral 10.

Forwardly extending arms 11 formed on the end plates are apertured to provide bearing openings for the outer cylindrical 85 ends of rock shafts 12. The inner cylindrical ends of these rock shafts are supported in bearings 13 on a bracket 14 secured by screws 15 to the cross bar 2 of the carriage. Each of the rock shafts 12 is angular in 90 cross section except at its reduced ends which are received in the bearings in the end plates and in the bearings of the bracket 14. A paper feeding, guiding or controlling device or paper finger, designated as a whole by the 95 reference numeral 16, is mounted on each rock shaft 12 to turn therewith into and out of operative position and for adjustment thereon longitudinally of the platen. Each rock shaft 12 extends beyond the associate 100 end plate 1 of the carriage and is fixedly connected to a bell crank lever 17. One arm 18 of this bell crank lever is connected to a contractile spring 19, which spring tends to

turn the bell crank lever and its associate rock shaft 12 to force the paper finger toward the platen. This arm is slotted at 20 for the reception of a pin 21 which limits the movement of the bell crank lever and the parts connected therewith in one direction. The other arm 22 of the bell crank lever is provided with a finger piece 23 by which the bell crank may be turned against the power of the spring 19 to move the paper feeding or controlling device 16 carried by the associate rock shaft away from the platen and out of coöperation with a work sheet 24 carried thereby. The paper guiding, controlling or feeding device 16 in the present instance comprises a sheet metal arm 25 formed at one end with a bearing or supporting portion 26 having a rectangular opening 27 therein to receive the associated rock shaft 12. The paper controlling device is thus connected to turn with the rock shaft but may be shifted longitudinally thereof to effect an adjustment of the paper feeding device longitudinally of the platen. The upper end of the paper feeding device is bifurcated to form arms 28 between which is received a margin feed roller 29 mounted to turn on a pivot 30 fixed in bearings 31 on the arms 28. A forwardly projecting finger piece 32 extends from the bearing portion 26 of each paper finger or controlling device 16 in order to facilitate an adjustment of the paper finger longitudinally of the platen. The parts thus far described constitute a portion of the usual equipment of a No. 10 or No. 11 Remington machine and further description thereof is deemed unnecessary.

From an inspection of Figs. 1 and 5 it will be seen that the rock shafts 12, by which the paper fingers are supported, are situated below the printing line indicated at *a* and that the fingers extend upwardly therefrom in front of the platen and across the printing line. It will also be seen that the usual key-hole slots 33 in the work sheets are arranged at the left-hand edge thereof and pass beneath the body portion of the paper finger in the backward and forward feed of the work sheet. In order to prevent the edges of the work sheet at the key-hole slots therein from engaging the supporting portion 26 of the paper finger and from catching in the space indicated at 34 (Fig. 1) between the lower end of the paper finger and the body portion thereof, I have provided a deflecting plate or guiding shield 35. This plate or shield extends in the general direction of the length of the paper finger and is secured thereto at one end by any suitable means. In the construction shown in Figs. 1, 2 and 5, this shield 35 is riveted to the paper finger at its upper end, as indicated at 36, and is preferably hard soldered to the paper finger at this end. I preferably reduce the thickness of the metal of the de-

flecting member 35 at the portion thereof which is secured to the body portion of the paper finger in order that the rearmost or contact surface of the deflecting member 35 will form substantially a continuation of the contact surface 37 of the paper finger itself and offer no obstruction on which an edge of the paper may be caught. This deflecting member 35 is resilient and conforms substantially to the contour of the platen except at the lower end 38 thereof, where it has a slight downward and forward curve just before it reaches the forward edge 10 of the paper apron. It will be observed that the deflecting member is flexed and extends away from the body portion of the paper finger as the deflecting member extends downwardly so as to cover the opening 34 in the supporting portion 26 of the paper finger, such supporting portion being received in part substantially between the two arms which constitute the paper guide, one of the arms being formed by the main body portion of the paper finger and the other by the deflecting plate or shield 35.

It will be understood that in the forward movement of the work sheet it will be maintained snug against the platen at all times until it leaves the margin feed roller 29 so that there is no opportunity for an edge of the work sheet to engage or be caught on any of the paper feeding devices. That portion of the work sheet which contains a key-hole slot 33 as it leaves the paper apron in the forward feed of the work sheet is immediately received beneath the deflecting member 35 and maintained snugly pressed against the face of the platen by the deflecting member 35. If any attempt is made to back up the sheet the deflecting member 35 maintains the edges of the key-hole slot snug against the platen until they pass the forward edge of the paper apron by which they are pressed against the platen. If the work sheet be fed forwardly to a position where the lower or bottom edge 39 thereof passes beyond the forward edge of the paper apron and the paper should be backed up from such position there is no liability of the bottom edge of the work sheet engaging the forward edge of the paper apron as the deflecting member 35 will accurately direct the edge of the work sheet into the slight space formed between the forward edge of the paper apron and the body portion of the platen. It will be understood, therefore, that I have provided simple and efficient means for accurately guiding and controlling the work sheet in such a manner that the edges thereof at the key-hole slots or at other portions of the work sheet are prevented from engaging or catching on any of the paper feeding or guiding devices or the means by which they are supported in place.

In Figs. 3 and 4 I have shown a modifica-

tion of the construction shown in Fig. 2. In this modified form of construction the parts which correspond to those previously described will be designated by the same reference numerals. In this modified form of the construction the deflecting plate or shield 35^a is formed integral with the body portion 25 of the paper finger and is in the nature of a spring tongue which projects rearwardly from the body portion of the paper finger from the point of attachment 40 where it joins the paper finger proper. The lower end of the deflecting member 35^a is curved slightly at 38^a substantially as in the previously described construction.

Otherwise the parts are the same as those previously described. It should be understood that any suitable means may be provided for connecting a spring deflecting member or shield 35 or 35^a to the paper finger to operate substantially in the manner set forth.

While I have shown the paper controlling device 16 at the left-hand end of the platen it will, of course, be understood that a similar device may, if desired, be provided at the right-hand end of the platen for controlling the work sheet at the right-hand as well as at the left-hand side edge portions thereof.

From the foregoing description it will be seen that in each of the constructions shown the paper finger has a deflecting member which extends from the body portion of the paper finger to a point where it is substantially flush with one edge of the supporting member 26; that in each of said constructions the paper finger is turned at one end to form a bearing and has a deflecting plate projecting from the body portion of the paper finger and extending over the turned end of the finger; that in each case the paper finger may be said to comprise two parts which are spaced apart at one portion of the paper finger and converge at another portion thereof to form in effect a continuous connecting surface made up in part of one member and in part of the other member, said members being united at the point of convergence; that in each instance the deflecting shield has its contact surface in register with the contact surface of the paper finger and forms in effect a continuation thereof; that the shield is fixed at its upper end to the paper feeding device or finger and is deflected therefrom at the lower end of the shield; and that in each instance the bar or supporting member 12 extends to the rear of a line coincident with or forming a downward continuation of the contact face 37 of the paper feed device and in the rear of a plane tangent to the front face of the platen, where the bar and the rear portion of the part 26 would offer an obstruction against which an edge of a sheet

might catch in the backward feed of the sheet were it not for the deflecting member 35 or 35^a.

What I claim as new and desire to secure by Letters Patent, is:—

1. In a front strike typewriting machine, the combination of a cylindrical platen, a paper feed device, a supporting member therefor which extends in the rear of a plane tangent to the front face of the platen, and a guiding shield which extends above the printing line and prevents an edge of a work sheet from catching on said supporting member as the edge passes the same.

2. In a front strike typewriting machine, the combination of a cylindrical platen, a paper feed device adjustable longitudinally of the platen, a supporting member for said paper feed device, said supporting member extending in the rear of a plane tangent to the front face of the platen, and a guiding shield connected at its upper end to and adjustable with said paper feed device, said shield co-acting with and preventing an edge of a work sheet from catching on said supporting member as the edge passes the same.

3. In a front-strike typewriting machine, the combination of a platen, a paper feeding device supported in front of the platen and beneath the printing line and extending upwardly from its support across the printing line, a supporting member for said device, and a guiding shield connected at its upper end to the paper feeding device and co-operating with an edge of a work sheet to prevent the same from catching on said supporting member.

4. In a front-strike typewriting machine, the combination of a platen, a paper feeding device supported in front of the platen and beneath the printing line and extending upwardly from its support across the printing line, means for affording an adjustment of said device longitudinally of the platen, a supporting member for said device, and a guiding shield extending above the printing line and adjustable with the paper feeding device longitudinally of the platen and co-operative with an edge of a work sheet to prevent the same from catching on said supporting member.

5. In a front-strike typewriting machine, the combination of a platen, a paper feeding device supported in front of the platen and beneath the printing line and extending upwardly from its support, means for affording an adjustment of said device longitudinally of the platen, a supporting member for said device, and a guiding shield co-operative with an edge of a work sheet to prevent the same from catching on said supporting member, said shield being fixed at its upper end to said paper feeding device.

- and being deflected therefrom at the lower end of the shield.
6. In a front strike typewriting machine, the combination of a paper finger, a support for said paper finger arranged below the printing line, and a shield which extends longitudinally in the direction of the length of the paper finger and with which the work sheets coöperate, said shield being fixed at 10 its upper end to the paper finger and being flexed at its lower end away from the body portion of the finger.
7. In a front strike typewriting machine, the combination of a paper finger, a support for said paper finger arranged below the printing line, and a shield which extends longitudinally in the direction of the length of the paper finger and with which the work sheets coöperate, said shield being fixed at 15 its upper end to the paper finger and having its contact surface in register with the contact surface of the paper finger and forming in effect a continuation thereof, the lower end of the shield being maintained away 20 from the body portion of said paper finger and extending substantially to the rear of said support.
8. In a front strike typewriting machine, a paper finger comprising two members which are spaced apart at the lower portion 30 of the paper finger and converge at the upper portion thereof to form in effect a continuous guiding surface made up in part of one member and in part of the other 35 member, said members being united at the point of convergence, and a support for said paper finger arranged where said members are spaced apart and substantially intermediate thereof.
9. In a front strike typewriting machine, the combination of a paper finger comprising two members which are spaced apart at one portion of the paper finger and converge at another portion thereof to form in effect 45 a continuous guiding surface made up in part of one member and in part of the other member, said members being united at the point of convergence, and a supporting portion substantially intermediate said members 50 at the portions thereof where they are maintained spaced apart, whereby an edge of a work sheet is prevented from catching on said supporting portion; and a bar located below the printing line and which is engaged by said supporting portion.
10. In a typewriting machine, a paper finger formed with a supporting member at one end and having a deflecting member which extends from the body portion of the 55 paper finger to a point where it is substantially flush with one edge of the supporting member to prevent an edge of a work sheet from catching on said supporting member.
11. In a typewriting machine, a paper finger formed with a supporting member at one end and having a deflecting member which extends from the body portion of the paper finger to a point where it is substantially flush with one edge of the supporting member to prevent an edge of a work sheet 60 from catching on said supporting member, and a margin feed roller carried by said paper finger at the end thereof opposite that which has the supporting member thereon.
12. In a typewriting machine, a paper finger turned at one end to form a bearing for supporting the finger adjustably in place and having a deflecting plate projecting from the body portion of the finger and extending over the turned end of the finger, 70 said deflecting plate coacting with a work sheet to prevent an edge thereof from catching on the turned end of the finger.
13. In a typewriting machine, a paper finger turned at one end to form a bearing 75 for supporting the finger adjustably in place and having a deflecting plate projecting from the body portion of the finger and extending over the turned end of the finger, 80 said deflecting plate coacting with a work sheet to prevent an edge thereof from catching on the turned end of the finger, and a margin feed roller carried at the opposite end of said paper finger.
14. In a typewriting machine, the combination of a supporting bar, a paper finger turned at one end to form a bearing portion which is supported on said bar, the paper finger extending upwardly in front of the platen from said supporting bar from a 90 point beneath the printing line, a deflecting plate which extends longitudinally of the paper finger and is fixed at its upper end thereto and terminates at its lower end adjacent to the supporting portion of the paper finger, said deflecting plate having its contact surface formed in effect as a substantial continuation of the contact face of the paper finger.

Signed at the borough of Manhattan, 110 city of New York, in the county of New York, and State of New York, this 22nd day of January, A. D. 1913.

CLIO B. YAW.
